UNITED STATES PATENT OFFICE.

JULIUS BRINKHOFF, OF PITTSBURG, PENNSYLVANIA.

VEGETABLE SLICER AND GRATER.

SPECIFICATION forming part of Letters Patent No. 290,390, dated December 18, 1882.

Application filed June 25, 1883. (Model.) Patented in Germany August 17, 1878, No 8,007.

To all whom it may concern:

Be it known that I, JULIUS BRINKHOFF, of Pittsburg, in the county of Allegheny and State of Pennsylvania, have invented certain new and useful Improvements in Vegetable Slicers and Graters, of which the following is a specification.

This invention has reference to an improved vegetable slicer and grater that is designed for the use of hotels, restaurants, and families, and adapted to slice or grate cabbage, cucumbers, radishes, beans, and potatoes.

In the accompanying drawings, Figure 1 represents an end elevation of my improved vegetable slicer and grater. Fig. 2 is a vertical transverse section on line $x-x$, Fig. 1, shown as used for grating. Fig. 3 is a vertical transverse section of the same on line $z-z$, Fig. 1, shown as arranged for slicing beans. Figs. 4 and 5 are respectively an end view and a plan of the bean-cutting attachment. Fig. 6 is an end view of the cutter-frame with a part broken away, drawn on a larger scale; Fig. 7, a side elevation; Fig. 8, a detail vertical transverse section on line $y-y$, Fig. 6, on a still larger scale; and Fig. 9, a wooden block for feeding forward the vegetables to be cut.

Similar letters of reference indicate corresponding parts.

30 A in the drawings represents the supporting standard of my improved vegetable slicer and grater. This standard is made of cast-iron, and provided with horizontal arms $a-a$, to which the supply-hopper B' of an upright casing, B , is attached by a suitable fastening device. Below the horizontal arms a extends in downward direction a bracket-shaped portion, a' , in the screw-socket of which a clamping-screw, C , is adjusted, which, in connection with the arms $a-a$, attaches the machine securely to a table or other support. The standard A is provided at one side with an upwardly-bent arm, A' , having a fixed horizontal arbor or shaft, a' , on which latter the revolving slicer or grater is supported. The upright casing B is further secured by lugs b and a transverse pin, b' , to the lower bracket part, a' , of the supporting-standard A , as shown in Figs. 1 and 2. The upright casing B is made of circular shape, with a guard-flange, b' , which is open at the lower part, and provided with side guide-rails, b^2 , to which a detachable recepta-

cle, B^2 , is applied by its grooved sides. The wall of the casing B is provided with a center opening for the passage of the horizontal shaft a^2 , and at one side of the same with a feed-opening, d , from which the supply-hopper B' extends at the outside of the casing B . A cutter-frame, D , composed of a flanged ring, D' , a center hub, f , and radial arms f' , connecting said ring and hub, is supported and adapted to turn on shaft a^2 at the inside of the casing B , being provided with a handle, f^2 , by which it is turned. Curved cutting-knives f^3 are attached to the radial arms f' of the frame D . 55 A sheet-metal disk, D^2 , for regulating the depth of cut or thickness of the slices cut off by the knives, is placed loosely on the hub f , and pressed toward the cutter-frame by a spiral spring, f^4 , which is attached at its outer end to the hub. This disk is provided with a number of slots, which allow it to pass the knives. An intermediate ring, D^3 , is interposed between the disk D^2 and the cutter-frame. This disk is provided with a series of lugs, f^5 , and the 60 cutter-frame has a corresponding number of inclined lugs (also marked f^5) facing the lugs of the ring. The ring D^3 is further provided with a fixed screw-post, f^6 , that is guided in an arc-shaped slotted extension, f^7 , of the cutter-frame 65 D , whereby the ring D^3 , on being taken hold of and moved in one direction along the inclined lugs f^5 of the cutter-frame and ring D^3 , forces the disk D^2 against the pressure of the spiral spring f^4 closer to the cutting-knives, or, when 70 moved in opposite direction, causes the moving of the disk by the action of the spiral spring f^4 away from the cutting-knives f^3 . After the disk D^2 has been adjusted to produce the required thickness of the slices, a thumb-nut, f^8 , on the screw-post f^6 is tightly clamped to the slotted extension f^7 , and thereby ring D^3 and spider-frame D' held rigidly in position. 75 As the cutting-knives f^3 pass close to the feed-opening d of casing B , by rotating the cutter-frame the vegetables fed through the feed-opening d are cut into slices of greater or less thickness, according to the greater or less distance of the disk from the edge of the cutting-knives. By the construction of the cutter-frame the disk D^2 may be quickly adjusted to any desired thickness of slices, the sliced portions being dropped back of the cutter-frame 80 along a convexo-concave disk-shaped guard- 85 90 95 100

adjustable guard or grating plate, E, that is secured back of the cutter-frame D, so as to drop broken pieces of vegetables into the receptacle B' at the lower part of the casing B.

15 In place of the cutter-frame D, a disk-shaped grater, F, may be used, as shown in Fig. 2, which is revolved by a center hub and handle on the shaft a' of standard A in the same manner as the cutter-frame D.

For cutting beans, a bean-cutting attachment, G, which fits into the feed-opening d, and

which is provided with a number of vertical inclined pockets, is attached in any suitable manner to the supply-hopper B', so that the beans are guided in inclined position and exposed to the slicing action of the cutting-knives.

For feeding the vegetables along the central bottom of the supply-hopper, a block, H, having a handle, H', Fig. 9, is used, by which the

20 vegetables can be pressed forward against the cutting-knives or grater without injury to the

30 fingers.

By my improved slicing and grating machine, large quantities of vegetables of different kinds can be cut up in a quick and regular manner, so that it is specially adapted whenever large quantities are required. It can be readily cleaned by being taken apart, as all the parts are detachable and can be readily

put together again.

Having thus described my invention, I claim

as new and desire to secure by Letters Patent—

1. The combination of a supporting vertical

35 standard provided with horizontal arms at its upper end and a horizontal bracket-shaped extension at its lower end, provided with a clamp-screw, an upwardly-bent arm attached to one of said horizontal arms, a flanged upright casing attached to said standard, a supply-hopper which rests upon said horizontal arms, a shaft 40 fixed to the upper end of said upwardly-bent arm and projecting through the center of said casing, and a rotary cutter supported upon said shaft within said casing, substantially as described.

2. The combination of a supporting-standard having a clamping device at its lower part and a horizontal shaft at its upper part, a flanged upright casing having a detachable bottom receptacle, a feed-opening, and a supply-hopper, a revolving and adjustable cutter-frame, and a detachable guard-disk back of the cutter-frame, substantially as set forth.

3. The combination, in a vegetable slicer and grater, of a supporting-standard, an upright casing having a feed-opening and a supply-hopper, a detachable bean-cutting attachment formed of tapering pockets, and an adjustable cutter-frame revolving on a horizontal shaft of the standard, substantially as specified.

In testimony that I claim the foregoing as my invention I have signed my name in presence of two subscribing witnesses.

JULIUS BRINKHOFF.
